UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

SAVINGS BANK.

1,403,854.

Specification of Letters Patent. Patented Jan. 17, 1922.

Application filed April 10, 1920. Serial No. 372,789.

To all whom it may concern:

Be it known that I, CHARLES FISHER, a citizen of the United States, residing at Chicago, in the county of Cook and State of Illinois, have invented a new and useful Improvement in Savings Banks, of which the following is a specification.

This invention relates particularly to a savings-bank of the type known on the market as a "library" safe.

The primary object of the invention is to provide an improved safe of this type, having one of the main side walls serving as a closure. A further object is to provide a construction for such a safe which will enable the safe to be manufactured conveniently and at moderate cost. An additional object is to provide improved locking mechanism for a safe of this character.

The invention is illustrated, in its preferred embodiment, in the accompanying drawings, in which—

Fig. 1 represents an inner plan view of the improved safe, the closure being in an abnormal open position to facilitate illustration, however; Fig. 2, an end view of the safe in closed condition; Fig. 3, an end view of the safe in the normal open position; Fig. 4, a view on an enlarged scale, corresponding with the view shown in Fig. 3, but showing a section taken as indicated at line 4 of Fig. 1; Fig. 5, a broken sectional view corresponding with Fig. 4, but showing the safe in locked condition; Fig. 6, a broken sectional view taken as indicated at line 6 of Fig. 1; Fig. 7, a broken sectional view taken as indicated at line 7 of Fig. 1; and Fig. 8, a broken section taken as indicated at line 8 of Fig. 7.

In the construction illustrated, the safe comprises a book-form casing A having one side A' adapted to serve as a closure; a locking member B disposed inside the longitudinal edge wall of the main casing-member A; and key-controlled means C for actuating the member B to unlock the safe.

The casing A affords one side wall, the back edge wall, the front edge wall, and the end edge walls of the book-form safe, the closure A' affording the other side wall of the safe.

In the preferred construction, the main casing A has a side wall 1 and a back edge wall 1^a formed integrally with each other, preferably from sheet-metal; and end edge

walls 2 and a front edge wall 2^a formed of brass. It is preferred to provide the walls 2 and 2^a by applying to the inner surface of the metal plate 1 an angle-form brass member, which may itself be formed from a strip of sheet brass, by bending the strip so as to form an angle. The angle is provided with an attaching flange 2^b, which is notched at points corresponding with the corners, as indicated at 3. The strip is then bent to form the three edge walls of the casing A, and the flange-portions 2^b are secured to the steel plate 1 by means of lugs 4 which are punched inwardly from the plate 1 and extend through perforations 4^a and clenched, as shown in Fig. 1. It will be noted that the walls 2 and 2^a are located a short distance inside the edges of the plate 1, so that said walls, which may be given a satin finish, will give the appearance of the gilt edges of the leaves of a book.

The cover-section, or closure, A', has applied to its inner surface an angle-form member which affords end flanges 5 and a longitudinal flange 5^a which are adapted to telescope with or fit inside of the walls 2 and 2^a of the section A. This member is provided with an attaching flange 5^b which is secured to the steel plate 6 of the closure A' by clenching lugs 7 formed integrally with the member 6. These clenching lugs extend through perforations 7^a with which the attaching flange 5^b is provided. The angle-form member which affords the flanges 5 and 5^a has the flange 5^b notched at the corners of the book, as indicated at 8, the member being bent into U-form, as appears from Fig. 1.

At the outer sides of the plates 1 and 6 may be employed padding 9, as indicated. The closure is suitably hinged to the free edge of the back wall 1^a; and the book is provided with a covering 10, preferably of leather, which is stretched over the sections and has its margin 10^a folded inwardly over the edges of the plates and secured between the inner surfaces of the plates and the angle-form members already described.

The metal plate 6 which constitutes the main portion of the closure A' is provided at its rear edge with inwardly off-set lugs 11, affording a channel, or shoulder, 11^a, as indicated in Fig. 4, against which the forwardly-turned edge of the back wall 1^a is adapted to bear. The back wall 1^a is

equipped with lugs 12 which are adapted to project between the lugs 11 and bear against the rear inner marginal surface of the plate 6. The purpose of the lugs described is to 5 maintain the rear edge of the plate 6 in pivotal relation with the free edge of the rear wall 1^a of the casing.

In the process of manufacture, a method is employed which tightly stretches the covering 10 over the sections of the safe when the parts are in the position shown in Fig. 4. Thus, the covering tends to hold the sections in proper pivotal relation. It is 10 preferred, however, to provide, also, a spring 13 which connects the cover A' and the casing-section A and tends to throw the cover-section to the open position shown in Fig. 4, and also tends to limit the cover-section 15 from swinging further open. The spring 13 is a leaf-spring secured by screws 13^a to the rear-portion of the inner surface of the plate 6. The spring is curved so as to be somewhat in the form of a V when the device is in the open condition shown in 20 Fig. 4. The free end portion 13^b of the spring bears on the inner surface of the plate 1, and the free extremity is lodged beneath or back of a catch, or lug, 14, with which the plate 1 is provided. This lug 25 may be provided by stamping the metal of the plate 1 inwardly, as shown in Fig. 4. It will be understood from Fig. 4 that the spring 13 serves to hold the cover-section A' in open position, and also that it tends 30 to prevent the cover-section from being swung open still further.

The longitudinal flange 5^c of the cover-section A' is provided with an inturned flange 5^d which is adapted to be engaged by 35 the longitudinally disposed locking member B. The member B comprises a strip of metal which is provided with slots, or perforations, 15, engaged by lugs 15^a which are formed integrally with the attaching flange 40 2^b of the angle-member which forms the end walls and front wall of the casing-section A. The lower or inner edge of the member B is in this manner pivotally connected with the casing A. The upper or outer 45 edge-portion of the member B is bent to afford a flange 16 which is adapted to engage the flange 5^c. The member B normally stands in the position shown in Fig. 4, and the locking engagement occurs in 50 the manner shown in Fig. 5, it being understood that the member B is automatically displaced by the flange 5^c when the sections are closed, and then springs into locking engagement.

55 The member B is provided at one end with an arm 17, which has therein a perforation 17^a into which projects a key-barrel 18. The key-barrel fits in a perforation in the end edge wall 2 of the safe and is confined in position by a clip 19 which is se-

cured to the wall 2 by means of rivets 19^a. The member B is adapted to be thrown to the locking position by means of a wire spring 20 which has one end resting upon the side wall of the safe, which has its intermediate portion passing freely through a retaining lug 19^b of the clip 19, and which has its other end secured, as indicated at 70 20^a, to the arm 17 of the member B. The arm 17 is equipped adjacent the perforation 75 17^a with a lug 17^b which is adapted to be engaged by a key inserted in the barrel 18, when the key is rotated. Thus, it will be understood from Fig. 6 that when a key is inserted and rotated in the proper direction, the bit of the key will strike the lug 17^b, and thus throw the locking member B away from the wall 2^a, thus releasing the locking flange 16 from engagement with the locking flange 5^c. 80

It will be noted from Fig. 1 that the locking flanges 5^c and 16 extend longitudinally the greater portion of the length of the casing-sections, so that the sections will be securely held together throughout their full 90 length. Also, the arm 17 of the locking member B is disposed adjacent the end edge wall 2 of the casing-section A, so as to be conveniently operated by a key inserted through said end wall. 95

One of the end edge walls 2 of the main casing-section A is shown equipped with a coin-slot 21 equipped with suitable slot-guards 21^a. This forms no feature of the present invention. It may be noted, however, that one 100 of the flanges 5 of the cover-section A' is cut away, as indicated at 5^d, so as not to interfere with the slot guard which is arranged on the inner side of the wall 2.

In the manufacture of the improved safe, 105 a suitable method is employed to apply the fabric or leather covering 10 to the plate 1, and the extension 1^a of said plate which forms the curved rear edge wall or back of the safe, the covering being tightly stretched 110 in this process and secured by applying the angle bar which provides the end edge walls 2 and front edge wall 2^a of the safe. The application of the covering 10 to the plate 6 is effected when the cover-section A' is in 115 the standing or partially standing position, the operation being such as to tightly stretch the cover, after which it is secured in the operation of applying the angle member which forms the flanges 5 and 5^a. 120

The construction described may be conveniently manufactured, presents an exceedingly neat appearance, and enables the safe to be opened in such manner as to fully expose the contents. In library safes upon the 125 market, it has been the practice to employ a rigid casing which forms the two sides and back of the safe, and provide a closure which forms the edge walls, or portion of the edge walls, which corresponds with the exposed 130

leaves of the book. This construction does not afford as complete access to the interior of the safe as is desirable. In other respects, also, the improved construction possesses 5 advantages over the previous constructions, as will be readily understood by those skilled in the art.

The foregoing detailed description has been given for clearness of understanding 10 only, and no unnecessary limitation should be understood therefrom, but the appended claims should be construed as broadly as permissible, in view of the prior art.

What I regard as new, and desire to secure by Letters Patent, is:

1. A book-form safe comprising two sections, one of said sections comprising a side wall and back edge wall, end edge walls and a front edge wall, the other section comprising 20 a plate forming the other side wall and having pivotal relation with the free edge of said back edge wall, a continuous flexible covering for said sections, means for locking the sections together, and coin-admission 25 means in one of said walls.

2. A safe comprising a plate affording a side wall and a back edge wall, a plate forming the other side wall and having pivotal relation with said back edge wall, a covering 30 extending over said plates and having its margins folded in over the edge-portions of the plates, a member secured to said first-named plate and serving to secure said covering thereto, said member affording end 35 edge walls and a front edge wall, a member secured to said second-named plate and serving to secure said covering thereto, said member presenting flanges adapted to telescope with relation to said end edge walls 40 and front edge wall, and means for releasably locking the safe.

3. A savings-bank comprising a main casing-section and a cover-section, said main casing-section comprising a plate having its 45 rear edge portion curved to afford a back edge wall, and an angle-form member applied to said plate near the edges thereof and affording end edge walls and a front edge wall, and said cover-section comprising 50 a plate having pivotal relation to said back edge wall and a flange member adapted to telescope with relation to the end edge walls and front edge wall of the main casing-section, and an integral covering applied to 55 said sections and having its marginal portions folded inwardly and secured between said angle-form member and the main plate and between said flange-member and the plate of said cover-section.

4. A savings-bank comprising a main casing-section provided with a rear edge wall, end edge walls, and a front edge wall, a cover-section having pivotal relation with the free edge of said rear edge wall, an integral covering applied to said sections, a

book-form spring interposed between the rear portions of said sections, means for releasably locking the front edge-portions of said sections together, and coin-admission means in one of said edge-walls. 70

5. A savings-bank comprising a main casing-section provided with a rear edge wall, end edge walls, and a front edge wall, a cover-section having pivotal relation with said rear edge wall, a covering applied to 75 said sections, a spring interposed between the rear portions of said sections and serving to open said cover-section and to limit the swing thereof, and means for releasably locking the front edge-portions of said sections together. 80

6. A savings-bank comprising a main casing-section and a cover-section, said main casing-section having a back edge wall, end edge walls, and a front edge wall, and said 85 cover-section having a pivotal support on the upper edge of said back edge wall, but without pintle connection, a covering applied to said sections and tending to hold the same in pivotal relation, and means for releasably locking said sections together. 90

7. A savings-bank comprising a main casing-section and a cover-section, said main casing-section having a back edge wall, end edge walls, and a front edge wall, and said 95 cover-section having a pivotal support on the upper edge of said back edge wall, but without pintle connection, a covering applied to said sections and tending to hold the same in pivotal relation, a spring interposed between the rear portions of said sections and adapted to throw the cover-section to the open position, and means for releasably locking said sections together. 100

8. A savings-bank comprising a main casing-section and a cover-section, said main casing-section having a back edge wall, end edge walls, and a front edge wall, and said cover-section having a pivotal support on the upper edge of said back edge wall, but 105 without pintle connection, a covering applied to said sections and tending to hold the same in pivotal relation, a spring interposed between the rear portions of said sections and adapted to throw the cover-section 110 to the open position and tending to limit the swing of the cover-section beyond the normal open position, and means for releasably locking said sections together. 115

9. A book-form savings-bank comprising 120 a main section and a cover-section, said main section comprising a plate having a curved rear wall, a brass angle strip applied to the front edge-portion and end edge- portions of said plate, said cover-section affording one side of the safe and being mounted in pivotal relation with respect to the upper edge of the back wall of the main section, a covering applied to said sections, a spring tending to throw 125 130

the cover-section to the open position, coin-admission means in one of said walls, and means releasably locking the cover-section to the main section.

- 5 10. In a savings-bank, the combination of a main casing-section comprising a plate having a curved portion affording a rear wall, an angle-form strip bent to afford end edge walls and a front edge wall, said strip 10 having an inturned flange secured to said plate, a ply of covering material applied to said plate and having inturned margins secured between the plate and the attaching flange of said strip, a cover-section connected to swing with relation to the upper edge of said back wall, and means for releasably locking said cover-section to the front edge portion of said main section.

15 11. In a book-form savings-bank, the combination of a main casing-section comprising a side plate, a rear edge wall, end edge walls and a front edge wall, a cover-section comprising a plate mounted to swing with relation to the upper edge of said rear edge 25 wall and equipped near its edges with a flange adapted to fit within the end edge walls and front edge wall of the main section, an integral covering over the side and back wall of the main section and over the 30 side wall of the cover-section, means tending to throw the cover-section to the open position, and means for releasably locking the front edge-portion of the cover-section to the front edge portion of the main section.

35 12. In a book-form savings-bank, the combination of a main casing-section provided with a rear edge wall, end edge walls, and a front edge wall, a pivotally mounted longitudinal locking member disposed adjacent 40 the inner side of said front edge wall, a cover-section mounted on the rear edge wall to swing with relation thereto, said cover-section being equipped at its front edge portion with a longitudinal locking member 45 adapted to be engaged by said first-named locking member, and means for actuating said first-named locking member.

13. In a savings-bank, the combination of a pair of casing-sections adapted to swing 50 with relation to each other, and which together form a box-like compartment, one of said sections being equipped with a locking flange at its longitudinal edge-portion, a pivotally mounted longitudinal locking member disposed in the other section near the front longitudinal edge thereof, said last-named locking member being adapted to swing, a spring adapted to throw said last-named member to the locking position, and 55 60 key-actuated means adapted to retract said member against the force of said spring.

14. In a savings-bank, the combination of a main casing-section having a rear edge

wall, end edge walls, and a front edge wall, a pivotally mounted longitudinal locking member 65 movably mounted in said section adjacent the front edge wall thereof, a spring adapted to throw said locking member to the locking position, key-controlled means mounted in one of the end edge walls 70 and adapted to retract said locking member, and a cover-section mounted to swing on said rear edge wall and equipped at its front edge portion with a longitudinal locking flange adapted to be engaged by said locking member.

15. In a savings-bank, the combination of a main casing-section comprising a side wall, a rear edge wall, end edge walls and a front edge wall, a pivotally-mounted longitudinal locking member adjacent said front edge wall and having an arm lying adjacent the end edge wall, a key-barrel mounted in said end edge wall for receiving a key adapted to retract said locking member through the 85 medium of said arm, a spring tending to throw said locking member to the locking position, and a cover-section mounted to swing on said rear edge wall and equipped at its front edge portion with a locking 90 member adapted to work between said first-named locking member and the front edge wall of the main casing-section.

16. In a savings-bank, the combination of a main casing-section comprising a side wall 95 having a curved portion affording a rear edge wall, an angle strip mounted on the inner surface of said side wall and having an inturned attaching flange, said side wall having integrally formed clenching lugs 100 engaging said attaching flange, a cover-section comprising a plate, said plate having its rear edge equipped with bearing lugs 105 engaging the upper edge of said rear edge wall and said rear edge wall having lugs 110 adapted to afford bearings for the rear edge of the cover-section plate, a spring interposed between the rear portion of the cover-section plate and the rear portion of the main section, an angle strip mounted on 110 the inner surface of said cover-plate and affording end flanges and a front flange adapted to be received telescopically within the end edge walls and front edge wall of the main section, said cover-section plate having 115 integral lugs engaging the inturned flange of said angle strip, a covering stretched over the side wall and back of the main section and over said plate of the cover-section, said covering having inturned margins secured between said angle members and said plates, and key-controlled locking means adapted to lock the front flange of said cover-section to the front edge portion of the main section.

CHARLES FISHER.
